FLUID-TIGHT CONTAINER BODY

William Edward Taylor, Fairfield, Conn., assignor to American Can Company, New York, N.Y., a corporation of New Jersey

Filed Dec. 1, 1961, Ser. No. 156,267

2 Claims. (Cl. 229—4.5)

The present invention relates to spirally wound fibre container bodies and has particular reference to such bodies wherein a narrow ribbon of an impervious material such as foil is used to seal the helical joint of the spirally wound body liner.

Because of the relative cheapness of fibre as opposed to metal, there has been a recent surge of interest in the use of spirally wound fibre bodies in containers for products which need not be subjected to heat processing. Since many such products are either liquid, as in the case of motor oil, or contain moisture, as in the case of biscuit dough, it is desirable that these bodies be provided with a lining which is completely impervious to the fluids contained in the product held by the container.

The usual way of obtaining this imperviousness in a spirally wound fibre body has been to form the inner or liner ply of the body of a material such as thin aluminum foil which is impervious to all fluids which are normally found in commercially packaged products. For the sake of economy, however, it is necessary to use very thin foil, generally less than .0005 inch in thickness.

Such thin foil is very weak and in order to adapt it for spiral winding on commercially available equipment, it is usually laminated to a strong backing material such as kraft paper. Unfortunately, this kraft paper is not impervious to fluids, and, when a kraft-backed foil web is spirally wound in the usual manner so that its edges are formed into a helical lap or butt joint, the edges of the kraft backing are exposed to the fluids in the container, with the result that these fluids wick into the kraft lining and eventually reach and impregnate the main fibrous body plies. This results in a softening of these main body plies and a consequent undesirable weakening of the container body.

The present invention contemplates a solution to this problem by providing a container construction wherein a narrow sealing ribbon of an impervious material such as foil or plastic is adhesively secured to the inside of the container body in such position that it overlies the joint of the fibre-backed inner foil liner and seals it off from the container product, thereby preventing the wicking of the product into the kraft backing. This is done by winding the sealing ribbon, which has its outer surface coated with an adhesive, onto the mandrel of the spiral winder, and then winding the kraft-backed liner ply onto the mandrel with its trailing edge centered on the sealing ribbon so that the helical joint of the liner is centrally disposed relative to the sealing ribbon. The same result may be achieved if the sealing ribbon is laminated to the liner ply as the two are fed toward the mandrel. As a result, there is provided an economical container body construction which is suitable for the packaging of many fluid products.

An object of the invention, therefore, is the provision of a lined, spirally wound container wherein the helical edge of the liner ply is sealed by a narrow sealing ribbon against penetration by the product.

Another object is the provision of a waterproof, moistureproof, greaseproof and oilproof spirally wound fibre container body which can be made economically on existing equipment.

Yet another object is the provision of a method of making such a container.

2

Numerous other objects and advantages of the invention will be apparent as it is better understood from the following description, which, taken in connection with the accompanying drawings, discloses a preferred embodiment thereof.

Referring to the drawings:

FIGURE 1 is a perspective view of a finished liquid-proof container embodying a spirally wound fibre body made according to the principles of the instant invention;

10 FIG. 2 is a section through the body of the container of FIG. 1, the view being taken substantially along the line 2—2 of FIG. 1;

15 FIG. 3 is a section similar to that of FIG. 2, but showing a container body embodying a slightly modified form of the invention;

20 FIG. 4 is a schematic view illustrating the various steps in making the liquid-proof fibre body of FIG. 3 on a spiral winding machine by the method of the instant invention; and

25 FIG. 5 is a fragmentary schematic view, similar to a portion of FIG. 4, showing a slightly modified method of making the body of FIG. 3.

As a preferred and exemplary embodiment of the instant invention, FIG. 1 discloses a sealed container 10 formed with a fibrous multi-ply, spirally wound body 12, the opposite ends of which are closed by means of metal end members 14 which are secured thereto in crimped or interfolded end seams 16 which may be of any desired liquid-tight configuration.

30 The container body 12 preferably is completely covered with a helically wound label ply 20 which is moisture and water resistant in order to prevent deterioration of the container in the event it is exposed to water or dampness during storage. For this purpose, the label 35 ply 20 may comprise a thin aluminum foil 22 which is laminated to a supporting kraft paper backing 24. The edges of the label ply 20 are preferably overlapped in a lap joint 26 to increase its resistance to water and moisture penetration.

40 The main wall portion of the body 12 is formed of two helically wound main body plies 28, 30 which are formed of a tough body stock such as kraft, chipboard, or the like to provide adequate strength. The edges of the main body plies 28, 30 are disposed in butt points 32, 34, respectively, which are offset one from the other, as clearly seen in FIG. 2.

45 The inner layer of the body 12 is formed of a helically wound liner ply 36 the inner surface of which is impervious to the product (not shown) which is packed in the container 10. The liner ply 36 preferably comprises a thin layer of aluminum foil 38 which is prelaminated to a kraft backing 40 which supports it and gives it strength so that it can be handled without tearing. The helical edges of the liner ply 36 are preferably butted together 50 to form a butt joint 42. Such a joint cannot be made accurately enough to completely shield the kraft backing 40 from the product in the container 10.

55 In order to shield it, a narrow, helically wound sealing ribbon or tape 44 of a material which is impervious to the product is adhesively secured to the inside surface of the liner ply 36 in such manner that it covers the butt joint 42 and prevents the product from gaining access to the kraft backing 40. In the container body of FIG. 2, the sealing ribbon 44 comprises a strip of unbacked aluminum foil which is of sufficient thickness that it can be handled without tearing during the body forming operations. Generally speaking, it is thought that aluminum foil having a thickness of .0005 inch or more is sufficiently strong so that it need not be laminated to a paper backing. 60 In the case of the sealing ribbon 44, however, which is comparatively narrow, it may be possible under some manufacturing conditions to use aluminum foil which is

somewhat thinner. The sealing ribbon 44 is preferably secured in place by a very thin film of a hot melt or pressure-sensitive adhesive (not shown) which is also impervious to the product so that it prevents seepage of the product between the sealing ribbon 44 and the foil layer 38 and into the kraft backing 40. The particular adhesive used forms no part of the instant invention, as its composition may vary according to the requirements of the particular container body being made. One suitable adhesive is the polyamide adhesive disclosed in United States Patent 2,840,264 issued to James H. Groves. Among other types of adhesives which are suitable are those comprising copolymers of vinyl chloride and vinyl acetate, either alone or in admixture with maleic anhydride or vinyl alcohol modified vinyl chloride-vinyl acetate copolymers. Although the sealing ribbon 44 is preferably formed of aluminum foil, it is not limited to such material and can be made of any suitable material which is impermeable to the product. Examples of such other materials are other metallic foils, and plastics such as polyethylene, polypropylene, etc.

FIG. 3 discloses a body construction which is somewhat different from the construction disclosed in FIG. 2. In this version, the label ply 20 and the two main body plies 28, 30 are similar to the corresponding plies of FIG. 2. However, the liner ply 36 is formed with a lap joint 46, instead of the butt joint 42, and the sealing ribbon 47 is formed of a two ply lamination, the outer layer 48, i.e., the one which faces the liner 36, comprising very thin aluminum foil which is supported by a suitable backing 49 which may comprise a kraft paper, cellophane, or a thin plastic such as polyethylene or the like. Here the impervious adhesive (not shown) is interposed between the aluminum foil ribbon layer 48 and the foil liner ply layer 38. The purpose of the backing 49 is to support the thin foil 48 during manufacture of the body, and the fact that the backing is exposed to the product in the container is immaterial.

FIG. 4 discloses the preferred method of manufacturing the container body 12. In this method, the body 12 is formed on a stationary mandrel 50 which is fixedly anchored at one end in a block 52, the other end of the mandrel 50 being free and unanchored. The sealing ribbon 44, its outer face coated with a suitable impermeable adhesive 54, is first wound onto the mandrel 50 at a point adjacent the block 52. Next, the liner ply 36 is butt wound onto the mandrel 50 with its trailing edge in alignment with the center line of the sealing ribbon 44 so that after one revolution around the mandrel, its leading edge is butted against its trailing edge to form the butt joint 42, which is centrally disposed beneath the sealing ribbon 44. The sealing ribbon 44 is firmly adhered to the inner surface of the liner ply 36 by the adhesive 54 so that it seals the butt joint 42 against the penetration of fluid. It may be desirable to space the adhesive 54 inwardly from the edges of the sealing ribbon 44 to prevent it from being squeezed onto the mandrel 50 during the winding operation. A continuous film of a suitable adhesive 56 is applied to the outside surface of the liner ply 36 as it approaches the mandrel 50.

The inner main body ply 30 is then butt wound over the liner ply 36 and is secured thereto by the adhesive 56. A suitable adhesive 58 is applied to the outside surface of the ply 30 as it approaches the mandrel 50. Next, the outer main body ply 28 is butt wound over the inner body ply 30 and is secured thereto by the adhesive 58. No adhesive is applied to the body ply 28.

The tube 60 which is formed by these plies is now passed beneath an endless winding belt 62 which operates around a driven drum 64 and an idler drum 66 and is looped around the mandrel 50 in tight driving engagement with the tube 60 to move it helically along the mandrel 50, and to pull the various plies which comprise the tube from the supply rolls which contain them. After the tube 60 passes from beneath the winding belt 62, the

label ply 20 is fed onto it to provide a decorative protective outer covering having the lap joint 26. The inside surface of the label ply 20 is coated with a suitable adhesive (not shown) to adhere it to the outer body ply 28. If desired, the label ply 20 may be printed with unitary label designs which are printed at an angle between the lines 68 and which, after winding, form complete unitary circumferential labels on the wound tube 60.

Thereafter, the tube 60 moves off the free end of the mandrel 50, and is cut along the lines 68 to form individual container bodies 12. It will be noted that the various adhesives which secures the plies of the body 12 together are not shown in FIGURES 2 and 3 for the sake of clarity of illustration.

FIG. 5 illustrates a slightly modified method of forming the bodies 12. This method differs from the just described method in that here the sealing ribbon 44 is laminated to the trailing edge portion of the liner ply 36 prior to the time these elements of the body 12 reach the mandrel 50. The outer surface of the sealing ribbon 44 is coated with the adhesive 54, just as in the method of FIG. 4, and the adhesive coated ribbon 44 and the liner ply 36 are brought together as they approach the mandrel 50 with the trailing edge of the liner ply 36 in alignment with the center line of the ribbon 44. The overlapped portions of the ribbon and liner ply 36 are then pressed together by a pair of pressure rolls 70 to prelaminate them and thus insure their registration as they are wound around the mandrel 50.

It is thought that the invention and many of its attendant advantages will be understood from the foregoing description and it will be apparent that various changes may be made in the form, construction, and arrangement of the parts and that changes may be made in the steps of the method described and their order of accomplishment without departing from the spirit and scope of the invention or sacrificing all of its material advantages, the form hereinbefore described being merely a preferred embodiment thereof.

I claim:

1. A fluid-tight container body for holding a fluid product, comprising:
at least on helical body ply which is pervious to the fluid product,
a helical liner ply disposed inwardly of said body ply, said liner ply comprising an inner layer which is impervious to the product and an outer backing layer which is pervious to the product,
the edges of said liner ply being disposed in a helical joint, and
a helical sealing ribbon disposed inwardly of said helical joint and covering it to prevent the product from gaining access to the pervious backing layer of said liner ply and said pervious body ply,
said sealing ribbon comprising a layer which is impervious to the product, said impervious sealing ribbon layer being disposed directly adjacent the inner impervious layer of said liner ply and being secured thereto on both sides of said helical liner ply joint by an adhesive which is impervious to the product.
2. A fluid-tight container body for holding a fluid product, comprising:
at least one helical body ply which is pervious to the fluid product,
a helical liner ply disposed inwardly of said body ply, said liner ply comprising an inner layer which is impervious to the product and an outer backing layer which is pervious to the product,
the edges of said liner ply being disposed in a helical joint, and
a helical sealing ribbon disposed inwardly of said helical joint and covering it to prevent the product from gaining access to the pervious backing layer of said liner ply and said pervious body ply,
said sealing ribbon comprising an outer layer which

is impervious to the product and an inner fibrous supporting layer,
said outer impervious sealing ribbon layer being disposed directly adjacent the inner impervious layer of said liner ply and being secured thereto on both sides of said helical liner ply joint by an adhesive which is impervious to the product.
